BALLOON CAP AND METHOD OF ITS
MANUFACTURE

William F. Huch, St. Paul, and Raymond I. Hakomaki, Minneapolis, Minn., assignors to General Mills, Inc., a corporation of Delaware

Application May 9, 1950, Serial No. 160,971

10 Claims. (Cl. 244—31)

1

The present invention relates to balloons and more particularly to an improved method of capping balloons made of thermoplastic sheet material.

Balloons are known in which the balloon body consists of a plurality of gores or sections of thermoplastic sheet material, these sections being seamed to each other at their adjacent edges to form a gastight bag. It has been customary in the prior art, in order to avoid seaming difficulties at the apex of the balloon, to make the end of each gore of definite width rather than having it taper to a sharp point. Thus the balloon body which is formed by joining the sides of adjacent gores will have top and bottom openings, at least one of which must then be capped in some manner.

It is one object of the present invention to provide a novel balloon cap which can be readily manufactured without the problem of intersecting seams at the apex of the balloon.

A further object is the provision of a balloon cap in which an integral tubular extension is provided at the balloon apex, this extension being closed and sealed and then covered by a protective cap.

Still another object is the provision of a novel balloon gore construction for use in the provision of an improved balloon cap.

A still further object is the provision of an improved method for the manufacture of such capped balloons.

Other objects and advantages will be apparent from the following specification in which a preferred embodiment of the invention is described.

In the drawings forming a part of this application, and in which like reference characters indicate like parts:

Figure 1 is a side elevation of one form of balloon which can be manufactured according to the present invention.

Fig. 2 is a plan view of a novel gore construction for use in such a balloon.

Fig. 3 is a plan view of a section of a balloon construction table or pattern suitable for use in production of the gore of Fig. 2 and in the assembly of such gores into a finished balloon.

Fig. 4 is an enlarged partial perspective view of the apex of the completed balloon body, prior to final closing and capping.

Fig. 5 is a perspective view similar to Fig. 4 showing the first step in the closing operation.

Fig. 6 is a similar perspective view showing the sealing of the balloon apex.

Fig. 7 is a top plan view of the apex of the

2 balloon after it has been sealed, capped, and taped, and

Fig. 8 is an enlarged sectional view on the line 8—8 of Fig. 7 showing details of the capping arrangement.

As shown in Fig. 1, the present invention has been described in connection with a balloon 20 having a spherical upper portion 22 and a conical or tapering lower section 24. The balloon body 10 consists of a plurality of vertically extending gores 26 which are seamed to each other at their adjacent edges in order to form a gasproof container. This balloon body is provided with a top or cap 68 overlapping the upper ends of the 15 individual gores.

A plan view of one of the individual gores 26 is shown in Fig. 2. Preferably a gore shape is utilized which is symmetrical with respect to a longitudinal center line indicated at 32. Thus 20 the gore has longitudinal edges 28 and 30, respectively, which taper in both directions toward the center line from an intermediate point of maximum width. Edges 28 and 30 of the gore substantially approach the center line at a point 25 34 corresponding to the apex of the desired balloon, and also at a point 36, which corresponds to the lower end of the balloon envelope.

According to one prior art method, the upper or apex end of the gore 26 would terminate at the point 34 in an end of definite width, so that adjacent gores could have their edges seamed to each other without having the seams actually intersect at the meeting point of the respective center lines. In such a case, the upper end of the balloon would have an opening of definite width, which would subsequently have to be capped. Since it was difficult in the use of mass production techniques to cap the circular opening at the apex of such a balloon by means of a welded or heat sealed seam, efforts have been made to provide a capping technique which would offer no manufacturing problem and which would result in a gastight envelope at this point.

According to the present invention, the upper end of each gore 26 is provided with a longitudinal extension 38 projecting beyond the point 34 which would normally be the upper end or apex of the gore. This extension 38 is symmetrical with respect to the center line 32, just as the individual gore edges 28 and 30 are.

A gore of the specific shape shown in Fig. 2, with the central or axial extension 38 at its apex end, can be advantageously manufactured on a pattern or balloon gore table 40 of the type shown 55 in Fig. 3. This table 40 is formed in substantially

the shape of one-half of the gore pattern. Thus table 40 has one straight edge 42 corresponding to the center line 32 of the desired gore.

The other edge 44 of the table 40 is shaped to correspond to the outer edge 28 or 30 of the gore 26. Thus this outer edge 44 tapers in both directions toward the straight edge 42 from an intermediate point of maximum table width. At what corresponds to the lower end of the gore, the edge 44 substantially meets the straight table edge 42 as shown at 46. The width of the table at point 46 is just large enough to secure a bottom opening of the desired size in the finished balloon.

At the apex or upper end of the balloon table 40, the edge 44 approaches almost to the line of the straight edge 42 at point 48 corresponding to the apex of the balloon. However, instead of intersecting the edge 42 along a line indicated by the dotted portion 48, as would be the case in the absence of the present invention, this particular table is formed with a projection or extension at the apex end so that the curved or contoured edge 44 includes an apex portion 52 extending parallel to the axis of the straight edge 42 and spaced slightly away from said axis. In order to strengthen the balloon table at this point, a portion corresponding to the extension may be widened as shown at 54 to provide the necessary rigidity. The extension as a whole is indicated by the reference 50.

In operation, the table shown in Fig. 3 is used for the production of balloons with tubular thermoplastic material according to one or more of the methods shown in the copending applications of Stinger et al., Serial No. 160,973, filed May 9, 1950, for Method and Apparatus for Manufacturing Balloons From Tubular Material, and Huch et al., Serial No. 160,972, filed May 9, 1950, for Balloon Manufacturing Method and Equipment, both of which are assigned to the owner of the 40 present application.

A strip of such tubular material is shown in phantom outline at 56 and it will be noted that one folded edge of the tubular strip is aligned with the straight edge 42 of the table to constitute the center line of the resulting gore. A strip can then be trimmed along a line corresponding to the table edge 44 and extension 52 to provide a gore section which, if unfolded, would have the complete shape shown in Fig. 2.

In the construction of a balloon with such gores, the adjacent edges 28 and 30 of the respective gores are seamed to each other to provide a strong and substantially gasproof balloon body. The seaming operation may be carried on with different types of equipment and with various methods, but is ordinarily practiced while the material is laid out on the balloon table 40, according to one of the methods of the above-mentioned patent applications.

Fig. 4 shows in partial perspective, the apex or upper portion of a balloon body made with the gores of Fig. 2. In the making of such a balloon, the edges of adjacent gores are seamed to each other at 37, and this seaming operation is carried out simultaneously between the edges of the extensions 38 at the apex of each gore. Thus seams 37 are provided between the individual gores 26, and these seams have continuations or extensions indicated at 39 between the edges of the respective gore projections 38.

Thus the seams 37 unite the gores to form the balloon body, while the seams 39 unite the extensions 38 of the gores to form an integral tubular extension 56 which projects from the apex 75

of the balloon 20. This tubular extension 56, since it is made by the same methods and with the same equipment as the remainder of the balloon body, will have the same characteristics of strength and resistance to diffusion.

As described above, the initial steps of our process include the formation of a plurality of gores corresponding to the particular type of balloon desired, each of said gores being provided with 10 an integral extension at one end. These extensions are sealed to each other in the same manner as the sides of the adjacent gores in order to form simultaneously a balloon body and an integral tubular extension at one end thereof, preferably the apex.

The next step in the process is illustrated at Fig. 5. According to this step it is necessary to close off the tubular extension 56 in some manner. While various methods can be used for the 20 formation of this closure, the preferred form of the invention involves the twisting of the tubular extension 56 so as to reduce its diameter to substantially the thickness of the individual layers of material. This twisting operation takes 25 place immediately adjacent the upper portion 22 of balloon 20, and the twisted portion is then tied or secured. A suitable tie may be made by the use of a nylon cord 58 knotted to itself at 30 60 to hold the twisted tubular extension in its closed condition.

As shown in Fig. 6, it is then possible to seal off the tubular extension beyond the tied portion by the use of a flame 62 from a portable burner 64 in order to form a bead or globule of molten 35 material at 66 which effectively seals off the upper end of the tubular extension 56. A heated wire or other sealer can also be used.

The resulting balloon body has the necessary resistance to diffusion at all points, including the tied and sealed extension 56. In order to cover and protect this tied and sealed extension, a circular cap 68 of thermoplastic sheet material is placed over the apex of the balloon as shown in Fig. 7. The cap 68 is then held in place by a series of load bearing tapes 70 which are passed across the cap 68 and the balloon body in such a manner as to overlie the individual seams 37 between the edges of adjacent gores. These load bearing tapes 70 cross over each other at the 45 exact apex of the balloon above the tied and sealed extension 56 and thus prevent any substantial strain from being placed on the balloon envelope or on the sealed tube.

These tapes 70 can then be extended downwardly over the entire length of the seams 37 and connected to a suitable load bearing ring at the lower end of the balloon body in the manner described and claimed in the Winzen Patent 2,526,719 assigned to the owner of the present 50 60 patent. As explained in said application, these load bearing tapes 70 accordingly distribute the load from the balloon load ring over all of the seams 37 and provide the necessary strength and rigidity for such seams. The tapes also carry the stresses at the upper section or apex of the balloon in order to prevent deformation of the balloon envelope and cap at this point.

According to the foregoing description, a balloon construction has been provided in which the individual balloon gores are formed of thermoplastic sheet material and are provided with an integral axial extension at one end. The adjacent edges of these gores of thermoplastic sheet material are then joined to each other; for example by a suitable heat seaming method and

apparatus, to provide a continuous balloon envelope. At the same time that the edges of adjacent gores are seamed to each other, the corresponding edges of the gore extensions are also joined. These joined extensions provide an integral tube at one end of the balloon. When this tube is located at the apex of the balloon, it is then tied and sealed to close said apex. The tied and sealed tubular extension is then capped and protected by a circular piece of similar thermoplastic material which is held firmly in place by load bearing tapes extending across both the cap and along the individual seams between the adjacent gores of the balloon envelope.

It will be understood that the thermoplastic sheet material which is utilized is relatively thin and that the apparent thickness of the tied tubular extension as shown in Figs. 5, 6, and 8 is of necessity exaggerated for clearness. The actual thickness of the material at this point is relatively small so that the tied and sealed tube rests beneath the cap 68 without substantial deformation of the balloon apex. The preferred materials for the construction of balloons according to the present invention are polyethylene sheet material for the gores themselves and cellulose acetate or nylon tapes coated with pressure sensitive adhesive, for the load bearing members 70.

Balloons made of these materials and capped in the manner described possess excellent resistance to diffusion as well as the necessary strength and rigidity for load bearing flights to substantial altitudes.

Since minor variations and changes in the exact details of construction will be apparent to persons skilled in this field, it is intended that this invention shall cover all such changes and modifications as fall within the spirit and scope of the attached claims.

We claim as our invention:

1. A balloon comprising a plurality of vertically extending gores of thermoplastic sheet material having their adjacent edges seamed to each other to form a gas tight bag, each gore having a relatively narrow integral extension at its apex, and the edges of adjacent extensions also being seamed to each other by extensions of the seams between adjacent gores to form a projecting tube of small diameter at the apex of the balloon, and means forming a gas tight closure for the tube.

2. A balloon comprising a plurality of vertically extending gores of thermoplastic sheet material having their adjacent edges seamed to each other to form a gas tight bag, each gore having a relatively narrow integral extension at its apex, and the edges of adjacent extensions also being seamed to each other by extensions of the seams between adjacent gores to form a projecting tube of small diameter at the apex of the balloon, securing means closing the tube adjacent the balloon apex, and a protective cap overlying the closed tube.

3. A balloon comprising a plurality of vertically extending gores of thermoplastic sheet material having their adjacent edges seamed to each other to form a gas tight bag, each gore having a relatively narrow integral extension at its apex, and the edges of adjacent extensions also being seamed to each other by extensions of the seams between adjacent gores to form a projecting tube of small diameter at the apex of the balloon, se-

curing means closing the tube adjacent the balloon apex, a protective cap overlying the closed tube, and a plurality of load bearing tapes overlying said protective cap and extending in superimposed relation along the seams between the gores.

4. A balloon according to claim 3 in which at least one load tape overlies each of the seams between adjacent gores and extends all the way from the apex of the balloon above said cap to the lower end of each gore seam.

5. A balloon according to claim 3 in which the protective cap is free of attachment to the balloon in the areas between the tapes.

15 6. A balloon gore having spaced longitudinal edges symmetrically located with respect to a longitudinal center line and converging toward the center line at each end of the gore, the gore having an integral, relatively narrow extension projecting at one end of the gore along said center line beyond the normal apex of the gore.

7. A balloon gore according to claim 6 in which the narrow extension has straight edges spaced symmetrically at each side of the center line.

25 8. A balloon gore according to claim 7 in which the straight edges of the narrow extension are joined to the longitudinal gore edges by smoothly curved portions.

9. A process for making and capping multiple-gore balloons which comprises forming a plurality of identical gores of thermoplastic sheet material, each gore having longitudinal edges spaced from a common center line and converging toward the center line at each end of the 30 35 gore, and each gore having a relatively narrow extension projecting axially from the end of the gore along the center line, successively seaming together the edges of adjacent gores and also seaming together the edges of adjacent extensions and thereby forming a hollow balloon body having an axial tubular extension at one end.

10. A process for making and capping multiple-gore balloons which comprises forming a plurality of identical gores of thermoplastic sheet material, each gore having longitudinal edges spaced from a common center line and converging toward the center line at each end of the gore, and each gore having a relatively narrow extension projecting axially from the end of the gore along the center line, successively 45 50 seaming together the edges of adjacent gores and also seaming together the edges of adjacent extensions and thereby forming a hollow balloon body having an axial tubular extension at one end, closing the tubular extension and folding it down on the balloon body, positioning a protective cap above the closed and folded down extension, and tapping the protective cap to the balloon body.
